FIG. 6

UNITED STATES PATENT OFFICE.

WILLIAM H. FROST, OF ETIWANDA, CALIFORNIA.

STORM-CURTAIN FOR AUTOMOBILES.

1,171,781.

Specification of Letters Patent. Patented Feb. 15, 1916.

Application filed March 12, 1915. Serial No. 14,012.

To all whom it may concern:

Be it known that I, WILLIAM H. FROST, a citizen of the United States, residing at Etiwanda, in the county of San Bernardino 5 and State of California, have invented new and useful Improvements in Storm-Curtains for Automobiles, of which the following is a specification.

My invention relates to a new and improved storm curtain for automobiles by which the opening formed above the door and between the side curtains and the roof of the top body may be closed, keeping out the storm and rain.

The principal object of my invention is to provide improved and novel means whereby the storm curtain may be quickly operated and securely fastened when it is desired to close the opening above the door 20 and which may be easily and quickly released. The curtain, when not in use, is positioned and concealed within the body of the door.

Another object of the invention is to provide means to effect a water-tight joint or seal between the outer face of the curtain and the upper part of the door on which the curtain is mounted, whereby any water running down the outer face of the curtain 30 will be diverted to the external face of the door and to the ground.

With these and other objects in view which will appear as the description proceeds, my invention consists in the construction and arrangement of parts shown and described and hereinafter claimed.

In the drawings which form a part of this specification, Figure 1 represents a side elevation of an automobile body showing my improved storm curtain in use. Fig. 2 40 shows a front elevation of my improved curtain. Fig. 3 shows a vertical cross-section taken through the center of the curtain and door. Fig. 4 shows a vertical cross-section of the upper part of the door with the curtain around the roller and the door lid covering the same. Fig. 5 shows a longitudinal horizontal section taken through the top of the door showing the curtain within 50 the door recess. Fig. 6 shows a detail view of curtain fastening members hereinafter referred to.

In the drawings, 10 represents the body of an automobile showing a front door 11 and 55 a rear door 12 provided with hinges 13 of any preferred construction. Above said car

body is top 14 provided with front curtain 15 and rear curtain 16. Between said side curtains and above rear door 12 is shown my improved storm curtain 17.

Referring now to Fig. 3, the upper part of door 12 is provided with a groove or channel 18 extending longitudinally along the upper edge of said door. Said groove 18 is provided with end bearings 19 and 20 in which studs 21 and 22 of curtain roller 23 are journaled. A storm curtain 24 of any suitable material is fastened to said roller at one end and is provided with a slat 25 at the other. Said roller is of the ordinary window-shade roller construction provided with means such as a helical spring 23' mounted within said roller, tending to wind the curtain around said roller. On the inner side and on the upper part of the top frame, 75 a pair of button-shaped slat supports 26 are provided which are adapted to engage curtain 24 when the same is in use. The corners of the free end of the curtain 24 are cut away, as shown at 27, to permit slat 25 to be hooked over the slat supports 26. On either side of the curtain opening are provided a plurality of curtain fastening devices mounted on side curtains 15 and 16, respectively; said devices, as shown in Fig. 6, consisting of a pair of resilient rods or bars 28 and 29, the member 29 being secured on the outer side of the side curtains while member 28 is secured on the inner side. Said curtain fastening devices are provided 90 at their free ends with a ball and socket joint 30 and 31. The ball joint is adapted to pass through perforation or eyelet 32 provided on either side of the curtain. It is evident from the construction of the curtain 95 fastening devices that the storm curtain may be fastened or unfastened to the side curtains either from the inside or the outside of the automobile.

Button-shaped slat supports 33 are mounted on the side wall of the groove 18 adapted to engage slat 25 when the storm curtain is wound up and not in use. Hinged along the external edge of the upper face of the door 12 is lid 34 adapted to form a closure over groove 18; the inner edge of said lid projecting slightly beyond the inner face of door 12 in order to facilitate the opening of said lid, as will be understood. A flexible flap 35 of any suitable material is sewed on or secured in any other suitable manner to storm curtain 24 with its free end extending

downwardly. Said flap 35 is secured to said storm curtain 24 at such a distance from roller 23 that the same will overlap lid 34 and extend for some distance thereon when 5 slat 25 is hooked over supports 26 and the curtain is in use. Lid 34 is mounted to door 12 by means of hinges 36 and 37, said hinges being provided with helical springs 38 which tend to close said lid over groove 18.

- 10 Operation: When it is desired to use the storm curtain, lid 34 is opened, slat 25 is unhooked from its supports 33 and the storm curtain is raised and hooked over supports 26 carried on the top frame. Springs 38 of 15 the hinges 36 and 37 will yieldingly hold lid 34 against the storm curtain and flap 35 will extend for some distance on the external face of lid 34. The storm curtain is now fastened to the side curtains 15 and 16 by means 20 of the fastening devices 28 and 29.

It is thus seen that I have provided an efficient storm curtain, easy in operation and effectively keeping out the storm. Any rain beating against the side of the automobile 25 will run down top flap 39 extending downwardly from the top frame 14 and the water flowing down the external face of curtain 24 will be diverted to the outer face of lid 34 and door 12 and to the ground by means 30 of the flexible flap 35.

While I have shown the specific construction of my improved storm curtain, it is obvious that various modifications may be made without departing from the spirit of

my invention, provided they fall within the scope of the claims.

I claim:

1. In combination, a body provided with a longitudinal chamber along its upper edge, a curtain roller mounted therein, a curtain having one end secured to said roller, curtain fastening means mounted on the other end of said curtain, a lid hinged to cover said chamber, means yieldably tending to close said lid over said chamber, and flexible means forming a water tight joint with the curtain and adapted to divert the water running down the curtain to the outer face of the body.

2. In combination, a body provided with a groove at its upper part, a curtain roller mounted in said groove, a curtain secured to said roller and adapted to wind thereon, means for holding the curtain in its unwound position, a lid covering said groove, means tending to close said lid, and a flexible flap secured to said curtain and adapted to form a water tight joint with the lid and divert water running down the curtain to the outer face of the body.

In witness that I claim the foregoing I have hereunto subscribed my name this 4th day of March, 1915.

WILLIAM H. FROST.
